CABLE STRAP FORMING APPARATUS

James R. Buchanan, South San Francisco, Calif.

Application August 30, 1954, Serial No. 453,167

5 Claims. (Cl. 153—32)

(Granted under Title 35, U. S. Code (1952), sec. 266)

This invention may be manufactured and used by or for the Government of the United States of America for governmental purposes without the payment of any royalties thereon or therefor.

This invention relates to forming dies and more particularly to dies for forming attaching straps capable of supporting multiple rows of cables or the like.

It is recognized practice to secure cables or pipes to a support by employing attaching straps that provide for an orderly cable arrangement and, in the case of moving vehicles, prevent cable vibration and accompanying noises. No difficulty has been experienced in bending attaching straps to accommodate a single row of cables to be supported; however, in forming straps to accommodate two rows of cables in nested relation, the problem has arisen of detachably securing the dies in the second row in selected relation to the first row to permit bending the strap material. At the present time the second row of dies is manually held on the first row, which procedure requires additional personnel, presents a safety problem, and limits the manufacture to a hand operation.

Accordingly, a principal object of this invention is to provide a double row die set capable of being interlocked in a strap forming position.

Another object is to provide releasable interlocking means that will permit the use of interchangeable dies.

Still another object is to provide an interlocked die set capable of being used in a conventional hydraulic, pneumatic or manual press.

Further objects are to provide a die set that will expedite and reduce the cost of manufacturing double row attach straps, and to provide a die set for forming various strap sizes and shapes capable of tightly embracing the cables to be supported.

These and other objects will become apparent from the accompanying drawing and detailed description.

According to the invention, the foregoing objects are achieved by a strap bending apparatus including two rows of interchangeable die members, each die member having a working surface corresponding to the contour of elongate members, such as a cable or pipe, to be accommodated by the strap. The dies can be detachably interlocked in various nested combinations in a manner to duplicate the over-all configuration of the desired cable arrangement.

In a specific embodiment, the readily detachable means for interlocking the two rows of die members comprises the provision of opposed longitudinal recesses in the adjacent flat die walls in one row, said recesses adapted to receive and clamp one or more depending extensions on each of the die members of the second row when the die members of the first row are secured together. The depending extensions may be pivotably anchored to their respective die members to permit these dies to be secured on the first die row in a position tilted from the longitudinal axis of the extension as may occur when the two adjacent dies of the first row between which the second row die rests, have a different radius of curvature.

In the drawing, Fig. 1, is a side elevation of a double row attaching strap formed by the die set of this invention for securing two rows of cables to a supporting structure; Fig. 2, a diagrammatic side elevation of an assembled die set on which is being formed the attaching strap; and Fig. 3 an exploded perspective view, partially in section, of the die set shown in Fig. 2.

Referring to Fig. 1 of the drawing, an attaching strap 2 formed by the die set of this invention is shown securing a double row of cables 4 or any other elongate members such as pipes, wires, etc. to a supporting structure 6. The upper row of cables is normally nested with the lower row, strap 2 being constructed to conform to the combined configuration of the cables to insure a snug fit and prevent lateral movement between the cables, strap and supporting structure that may cause vibration, noise, and cable breakdown.

The die set in Figs. 2 and 3 is generally indicated by reference numeral 8 and comprises a first row 10 including two or more die members 10a to 10d, and a second row 12 including one or more die members 12a and 12b adapted to be nested with the first die members.

The working surface on each die member has a configuration corresponding to the cable to be accommodated by the strap, which in the illustrated embodiment are substantially cylindrical. Both rows of die members are interchangeable and a sufficient stock of different size dies is maintained to provide as many combinations as are necessary to duplicate the desired cable arrangement.

The dies in first row 10 are provided with rectangular bases 13 adapted to be supported on a tray 14 in any suitable manual or power-operated press, not shown, and fixed thereon by a clamp 16 which compresses the dies in the selected assembly. As will be presently described,

clamp 16 also functions to secure the die members in second row 12 in their nested position on the first row. The dies in both first and second rows are interlocked by means which comprise one or more longitudinal recesses 18 constructed preferably in the opposing flat die walls

20 of lateral die members 10a to 10b in the first row. Each pair of opposing recesses 18 cooperate to form a socket to receive and anchor a correspondingly shaped pin 22 extending from die members 12a and 12b of the second row when the die members of the first row are clamped as described above. The width of the die members will of course depend primarily on the strap dimensions. Sufficient pins 22 should be provided on each die member to withstand the sheer component of the press force in forming the strap. The cross-sectional shape of

recesses 18 and pin 22 may vary, although a circular shape is preferred because it offers the maximum bearing surface and is simple in construction. Although recesses 18 may be constructed in only one die wall of adjacent dies it is preferred to provide recesses in both opposing walls 55 to insure uniformity in dies which are interchangeable.

When working surfaces are round as shown and adjacent dies have different radii, it is necessary to permit second row die members 12a and 12b to move relative to their pins 22 so that the die members can be securely

seated on both adjacent working surfaces of the lower die members. Die members 12a and 12b are completely round in cross-section to provide a two point contact with the lower adjacent surfaces and, also, because the effective working or strap-forming surfaces of die members 12 will vary in circumference depending on the radii of the lower adjacent working surfaces. Referring to Fig. 2, relative movement between the upper die members and their anchoring pins 22 is accomplished by forming the upper end of each pin with an eye portion 24

70 through which is freely passed a shaft 26 secured in the ends of the die members. The central portion of each die member is slotted at 28 to permit the member to

move freely to either side of the pins to a position determined by the adjacent die.

Operation of the die set is described with reference to Fig. 2 wherein the first and second rows of die members have been assembled in a predetermined relation according to the selected arrangement of cables 4 to be accommodated, as shown in Fig. 1. Both rows of die members are secured by clamp 16 on tray 14 which is mounted in the press. It should be noted the lateral walls of the lower die members are in abutting relation to insure uniformity between the formed strap and cable arrangement. A blank of strap material 30 is positioned over the nested dies, one end of the strap material being secured by a press member 32 and the remaining strap material successively held and bent over each die working surface by a holding press member 34 and a bending press member 36, and the opposite end finally being formed by a press 38. Obviously, other press arrangements can be used which will bend the strap material at one time or, conversely, the strap may be manually formed by hammer and chisel.

By use of the foregoing invention, multiple row attaching straps can be formed manually or by any suitable press in a safe and expeditious manner. This result is achieved by providing an interlocking means that prevents accidental separation of the dies during the strap forming operation. The interlocking means is operated automatically as the dies are clamped in their assembled relation and enables all die members to be interlocked in the same manner so that they can be interchangeable.

Obviously, many modifications and variations of the present invention are possible in the light of the above teachings. It is, therefore, to be understood that within the scope of the appended claims the invention may be practiced otherwise than as specifically described.

I claim:

1. Apparatus for forming supporting straps for nested upper and lower cable-like members, said apparatus including a bottom row of interchangeable independent die members adapted in height and surface curvature for forming when adjacently disposed an upper surface conforming in over-all curvature with the upper surface of said lower nest-forming cable-like members, an upper die member conformed in size and curvature with an upper cable-like member, and means for holding said upper die member firmly in a nested position on said adjacently-disposed lower die members, said means including an arm pivotally carried by said upper die member and adapted to extend through the meeting surfaces of said adjacently-disposed bottom row die members, said meeting surfaces being recessed for closely receiving said arm and maintaining said nested relation.

2. Apparatus for forming supporting straps for nested upper and lower cable-like members, said apparatus including a bottom row of interchangeable independent die members adapted in height and surface curvature for forming when adjacently disposed an over-all upper surface conforming in curvature with the upper surface of said lower nest-forming cable-like members, an upper die member conformed in size and curvature with an upper cable-like member, means for holding said upper die member firmly in a nested position on said adjacently-disposed lower die members, said means including an arm pivotally carried by said upper die member and adapted to extend through the meeting surfaces of said adjacently-disposed bottom row die members, said meeting surfaces being recessed for closely receiving said arm, and means for pressing together said bottom row of die members whereby said bottom members securely grip said arm for maintaining said nested relationship.

3. Apparatus for forming supporting straps for nested upper and lower cable-like members, said apparatus in-

cluding a bottom row of interchangeable independent die members adapted in height and surface curvature for forming when adjacently disposed an over-all upper surface conforming in curvature with the upper surface of said lower nest-forming cable-like members, an upper die member conformed in size and curvature with an upper cable-like member, and means for holding said upper die member firmly in a nested position on said adjacently-disposed lower die members, said means including an arm pivotally carried by said upper die member and adapted to extend through the meeting surfaces of said adjacently-disposed bottom row die members, said meeting surfaces being recessed for closely receiving said arm and maintaining said nested relation, and said arm having its pivotal axis sufficiently displaced radially from the central axis of said upper die member for permitting said arm to align itself with said recess under varying nested dispositions.

4. Apparatus for forming supporting straps for nested upper and lower cable-like members, said apparatus including a bottom row of interchangeable independent die members adapted in height and upper surface curvature for forming when adjacently disposed an overall upper surface conforming in curvature with the upper surface of said lower nest-forming cable-like members, an upper die member conformed in size and curvature with an upper cable-like member, means for holding said upper die member firmly in a nested position on said adjacently-disposed lower die members, said means including an arm pivotally carried by said upper die member and adapted to extend through the meeting surfaces of said adjacently-disposed bottom row die members, said meeting surfaces being recessed for closely receiving said arm, and means for pressing together said bottom row of die members whereby said bottom members securely grip said arm for maintaining said nested relationship, said lower die members having flat-surfaced bottom and side walls and said pressing means acting upon said side walls, whereby said walls of said lower die members are pressed into flush contact.

5. Apparatus for forming supporting straps for nested upper and lower cable-like members, said apparatus including a bottom row of interchangeable independent die members adapted in height and upper surface curvature for forming when adjacently disposed an over-all upper surface conforming in curvature with the upper surface of said lower nest-forming cable-like members, an upper die member conformed in size and curvature with an upper cable-like member, means for holding said upper die member firmly in a nested position on said adjacently-disposed lower die members, said means including an arm pivotally carried by said upper die member and adapted to extend through the meeting surfaces of said adjacently-disposed bottom row die members, said meeting surfaces being recessed for closely receiving said arm, and means for pressing together said bottom row of die members whereby said bottom members securely grip said arm for maintaining said nested relationship, said lower die members having flat-surfaced bottom and side walls and said pressing means acting upon said side walls whereby said walls of said lower die members are pressed into flush contact, the height of said walls being fixed in accordance with the upper surface curvature of each lower die member.
